UNITED STATES PATENT OFFICE.

PHINEAS F. KING, OF CHICAGO, ILLINOIS, ASSIGNOR OF ONE-HALF TO
ALEXANDER P. O'HARA, OF SAME PLACE.

DESIGN FOR A SADDLE FOR BICYCLES.

SPECIFICATION forming part of Design No. 25,486, dated May 12, 1896.

Application filed February 3, 1896. Serial No. 577,937. Term of patent 7 years.

To all whom it may concern:

Be it known that I, PHINEAS F. KING, a citizen of the United States, residing at Chicago, in the county of Cook and State of Illinois, have invented and produced a new and original Design for Bicycle-Saddles, of which the following is a specification, reference being had to the accompanying drawings, in which—

10 Figure 1 is a plan view of the seat-rim and horn of the saddle. Fig. 2 is a side view of the seat. Fig. 3 is a rear view of the seat, rim, and horn.

The principal features of my design consist in an extended horn A and an elliptical seat B, made up of a rim B², which rim extends and is prolonged into the horn A, as shown more clearly in Fig. 1. The rim B² also slopes downwardly from the horn, as shown in Fig.

2, and is upturned at its rear edge to a point 20 above the vertical plane of the horn A. The seat B of the saddle also approximately follows the line of the curve of the rim rearward from the horn, and said horn is hollowed out, as shown in Fig. 3. 25

Another feature of my design is the form of the rim of the seat, as shown in cross-section.

What I claim is—

The design for a bicycle-saddle substantially as herein shown and described. 30

In testimony whereof I affix my signature in presence of two witnesses.

PHINEAS F. KING.
